US0D1102015S

(12) **United States Design Patent** (10) **Patent No.:** **US D1,102,015 S**
(45) **Date of Patent:** **** Nov. 11, 2025**

(54) **ELECTRIC ATOMIZER**

(71) Applicant: **Shenzhen VapeEZ Technology LTD**,
Guangdong (CN)

(72) Inventors: **Laizhi Song**, Guangdong (CN); **Wen Yang**, Guangdong (CN); **Jinglian Shi**,
Guangdong (CN)

(73) Assignee: **SHENZHEN VAPEEZ TECHNOLOGY LTD**, Guangdong
(CN)

(**) Term: **15 Years**

(21) Appl. No.: **29/893,009**

(22) Filed: **May 24, 2023**

(30) **Foreign Application Priority Data**

Apr. 13, 2023 (CN) 202330202216.6

(51) **LOC (15) Cl.** **27-07**

(52) **U.S. Cl.**

USPC **D27/162**

(57) **CLAIM**

The ornamental design for an electric atomizer as shown and described.

DESCRIPTION

FIG. 1 is a front perspective view of an electric atomizer showing our design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures depict portions of the electric atomizer that form no part of the claimed design.

1 Claim, 8 Drawing Sheets
